UNITED STATES PATENT OFFICE.

JOHN WILLIAM ARROWSMITH, OF CENTER LINE, MICHIGAN.

TELEPHONE ATTACHMENT.

Application filed December 1, 1926. Serial No. 151,968.

The present invention relates to improvements in attachments for telephones, and the primary object of the invention resides in the provision of a combination memorandum and mirror attachment primarily intended for use upon desk telephones.

A further object of the invention resides in the provision of a telephone attachment embodying a freely movable main body portion which when disposed in one position, paper will be exposed for the purpose of making notations or taking down other data, and when moved to its opposite position, a mirror will be exposed to view.

A further object of the invention resides in the provision of a combined memorandum and mirror attachment for telephones, embodying a pivotally mounted main body portion so supported as to be automatically retained in either of its adjusted positions.

A still further object of the invention resides in the provision of a device of this character which is of extremely simple and durable construction, and one embodying novel features of assembly, in that certain sections of the device so interfit with companion sections as to eliminate the necessity of but a minimum number of fastening elements for retaining the separable sections in assembled relation.

A still further object of the invention resides in the provision of a memorandum attachment for telephones wherein the writing material is in the form of a roll of paper, and which is trained over a suitable writing surface, with the device so constructed at one end as to permit of the used portion of the paper strip to be withdrawn and readily severed along one edge of the device.

Other objects and advantages of the invention will be apparent during the course of the following detailed description, taken in connection with the accompanying drawing forming a part of this specification and in which drawing:

Figure 1 is a perspective view of a conventional type of desk telephone and showing the improved attachment applied thereto and with the mirror exposed to view.

Figure 2 is a face plan view of the writing side of the main body portion of the device and showing portions broken away for illustrating certain details of construction.

Figure 3 is an enlarged central longitudinal section on line 3-3 of Figure 1, and

showing by way of dotted lines, the manner in which the main body portion may be pivotally swung for exposing either face thereof to a position facing a person using the telephone.

Referring to the drawing in detail, and wherein similar reference characters designate corresponding parts throughout the several views, the letter A designates a conventional type of desk telephone to which the improved attachment is shown applied, the attachment embodying a supporting means B and a main body portion or attachment proper C.

The telephone A, and which is of the conventional desk type, embodies the usual base 5 and the upright standard or post 6 which is usually of cylindrical formation.

The supporting means B, embodies a pair of clamping plates 7 each being provided with semi-circular shaped portions 8 which may be clamped about the telephone post 6 at any preferred height therealong by means of a suitable bolt and wing nut 9, the bolt 75 extending transversely through the clamping plates and being threaded for receiving the wing nut. Mounted horizontally at the outer end of the clamp formed by the plates 7, is a bracket arm 10 which is preferably of cylindrical formation, and which arm may be of any desired length for disposing the attachment proper C at any preferred distance from the telephone post 6.

Carried by the outer end of the bracket arm 10, is a U-shaped keeper or rest 11 embodying inner and outer parallel arms 12 and 13 respectively, connected at their lower ends by means of a stop section 14 which extends in parallel alignment with the bracket 95 arm 10. The upper end of the inner arm 12 is connected to the bracket arm 10 at a point slightly inwardly from the outer end thereof for providing a terminal bearing portion 15 at the outer end of the bracket arm, while the upper end of the outer arm 13 is offset inwardly at a right angle for forming a bearing portion 16 which extends in axial alignment with the bracket arm bearing portion 15.

By observing Figures 1 and 3, it will be seen that the keeper arms 12 and 13 extend downwardly and forwardly, thus disposing the horizontal stop section 14 at a location forwardly and below the companion bearing portions 15 and 16. The horizontal stop section 14 may of course be disposed at any location forwardly and below the axis of the

bearing portions 15 and 16, in accordance with the desired angle at which it is preferred that the attachment proper C be disposed. The horizontal stop section 14 may be provided with a pair of rubber bumpers 17 so arranged as to engage the attachment proper when swung to either of its adjusted positions.

Referring now to the attachment proper 10 C, and which is adapted to be freely mounted upon the outer end of the supporting means B, the same embodies a substantially rectangular shaped frame 20 which may be formed from sheet metal, shaped to provide 15 channel shaped side rails 21 embodying base or web portions 22 and inwardly extending flanges 23. Connecting one end of the flanges 23 at the memorandum side of the frame, is a cross plate 24 having a straight outer edge 25 provided with a semi-circular shaped notch 26 which is preferably disposed midway of the ends of the plate. Connecting one end of the oppositely disposed flanges 23 at the mirror side of the 20 frame, and at that end of the frame at which the cross plate 24 is provided, is a retaining plate 27 provided at its outer edge with an inwardly extending flange 28 which is directed toward the cross plate 24 with the inner edge of the flange spaced from the inner face of the cross plate. This flange 28, and as will be seen by observing Figures 1 and 3, extends transversely of the frame 20 at a point inwardly of the straight outer edge of 30 the cross plate 24. Formed at the opposite end of the side rails 21, and connecting the ends of the rails, is a semi-circular shaped head 30 which forms a terminally opening pocket for receiving a roll of paper 31.

40 Thus it will be seen that the flanges 23, cross plate 24, and head 30 provide a window 32 at the memorandum side of the frame, and that the companion flanges 23, retaining plate 27, and head 30, provide a window 33 at the mirror side of the frame.

45 Fitting in the frame 20, is a U-shaped carrier 34 embodying side arms 35 fitting in the channel shaped side rails 21, and a cross arm 36 which engages the flange 28 of the retaining plate 27. As will be observed in Figure 2, the arms 35 engage the webs of the side rails 21, and that the free ends of the arms extend into the pocket formed by the head 30. Provided in the free ends of the carrier 50 arms 35, and at the confronting faces of the arms, are terminally opening guideways or grooves 37 into which the ends of a shaft 38 may extend for supporting of the paper roll 31. The carrier 34 may be rigidly secured 55 within the frame 20 by means of suitable screws or rivets 39 which extend through the webs of the side rails 21.

60 Removably fitting over the head 30, is a cap 40 of semi-circular shape in cross section, 65 and which cap is adapted to be snapped over

the head 30 for closing the outer end of the head and forming a suitable container for the paper roll 31. The cap 40 may be provided with flaring lips 41 for permitting of ready removal of the cap from the head 30. 70

Arranged in the U-shaped carrier 34, and opening at the window 33, is a suitable mirror plate 42 the side edges of which preferably engage the confronting faces of the carrier arms 35, and one end of the plate 75 42 engaging the carrier cross arm 36 at the inner edge of the arm. As will be seen in Figure 3, this mirror plate 42 terminates short of the pocket for receiving the paper roll 31. 80

Arranged over the back of the mirror plate 42, is a writing plate 44 which is preferably made of thin sheet metal, with one end of the plate curled as at 45 for abutting against the outer side of the flange 28 when 85 the writing plate is in assembled position behind the mirror plate 42. The opposite end of the writing plate is bent over one end of the mirror plate as at 46, and which as will be apparent, prevents relative longitudinal 90 movement of the plates 42 and 44. This writing plate 44 is of greater area than the window 32, and preferably has its side edges 95 extending into the channel shape side rails 21 in a manner for preventing lateral shifting of the writing plate when the device is being used for writing purposes.

A strip of paper from the roll 31 is fed over the writing plate 44 at the window 32 and at its free end extends inwardly of the 100 cross plate 24. After that portion of the paper exposed at the window opening 32 has been used for taking down the desired data, the operator may grasp the lower end of the paper at the notch 26 and after withdrawing the used portion of the paper the same may be readily severed along the straight outer edge 25 of the cross plate 24. 105

The attachment proper C is pivotally mounted by its side rails 21 upon the bearing portions 15 and 16 of the supporting means, with the pivotal axis of the attachment disposed nearer to the head 30 than to the cross plate 24, and at a location whereby the end of the frame carrying the head, is overbalanced by the opposite end of the frame. The bearing portions 15 and 16 may extend for a slight distance into the carrier arms 35 for providing a suitable bearing for the attachment C. By observing Figure 3 it will be seen that by so having the cross-plate-carrying end overbalance the head-carrying end, that when the attachment proper is swung about the pivot point "x" for exposing the mirror side of the attachment, that the head 30 engages the rubber bumpers 17 of the stop section 14 for retaining the attachment C at the desired angle, and that when the attachment C is swung to the position of the dotted line showing for exposing the paper, the 110 120 125 130

cross-plate-carrying or heavier end of the attachment comes to rest upon the bumpers 17 of the stop section 14 for disposing the paper in a position whereby notations or other data 5 may be readily made upon the paper. Thus it will be seen that the attachment proper C is so pivotally mounted upon the supporting means B as to be automatically retained in either of its adjusted positions.

10 It may here be well to state that the U-shaped carrier 34 aside from serving as a reinforcement for the frame 20 and as a carrier for the paper roll 31, also serves as 15 means for overbalancing the attachment C at one side of its pivotal mounting upon the supporting means B.

In the assembling of the device, the U-shaped carrier 34 may first be inserted through the open head 30 and secured to the frame 20 as by means of the rivets 39. The mirror plate 42 may then be inserted through the open head 30 and after which the writing plate 44 may be inserted from the opposite end of the frame until the curled flange 45 25 engages the flange 28 and then the opposite end of the writing plate bent over the end of the mirror plate as at 46 in a manner whereby the plates 42 and 44 are held against longitudinal movement within the frame 20.

30 The curved portion 46 of the writing plate also aids in guiding the paper from the roll 31 over the writing plate.

When all of the paper has been used from the roll 31, the cap 40 may be removed from 35 the head 30 and a new roll of paper positioned in the pocket of the head.

From the foregoing description it will be apparent that a novel and efficient attachment for use in connection with desk telephones has been provided, embodying a freely movable main body portion which when disposed in one position, paper will be exposed for the purpose of making notations, and when moved to its opposite position, a 45 mirror will be exposed to view, and which main body portion is so pivotally mounted as to remain in either of its adjusted positions without the necessity of employing keeper means for retaining of the main body 50 portion in its adjusted positions.

Changes in detail may be made to the specific form of the invention herein shown and

described, without departing from the spirit of the invention or the scope of the following claims.

55

I claim:

1. A device of the class described comprising in combination, a supporting means including a clamp portion for attachment to a telephone standard and a U-shaped keeper portion embodying a stop section, and an attachment proper pivotally carried by the supporting means and engageable with said stop section for retaining of the attachment proper in adjusted positions with either face 60 thereof exposed to view.

2. A device of the class described comprising in combination, a bracket arm adapted to be mounted horizontally upon a telephone standard and provided at its outer end with a bearing portion, a U-shaped keeper carried by the bracket arm and embodying a stop section arranged forwardly and below a bracket arm and a bearing portion disposed in axial alignment with the bearing portion 70 of the bracket arm, and an attachment proper pivotally mounted off center upon said bearing portions and freely engageable with said stop section for retaining the attachment proper in either of its adjusted positions for exposing either face of the same.

3. In a memorandum attachment for telephones, the combination of a support provided with aligning bearing portions, a frame pivotally mounted intermediate its 85 ends upon said bearing portions and provided with a window opening, means on one end of the frame for mounting a paper roll with its free end trained through the frame beneath said window opening for withdrawal 90 at the opposite end of the frame, and a stop carried by the support and disposed in a plane between the vertical and horizontal planes of the support.

4. A device of the character described 95 comprising, a supporting member, a frame pivotally mounted on the supporting member, and a stop carried by the supporting member, said stop being adapted to engage either flat face of the frame over the entire 100 width thereof to hold the frame in a slanting plane.

JOHN WILLIAM ARROWSMITH.
